UNITED STATES PATENT OFFICE.

CESAR ORSINI, OF ROME, ITALY.

DESIGN FOR A MEDAL.

SPECIFICATION forming part of Design No. 22,335, dated April 11, 1893.

Application filed March 6, 1893. Serial No. 464,902. Term of patent 7 years.

To all whom it may concern:

Be it known that I, CESAR ORSINI, of Rome, Italy, have invented and produced a new and original Design for a Medal, of which the following is a specification, reference being had to the accompanying drawings, forming a part of this specification, in which—

Figure 1 represents the obverse side of the medal; and Fig. 2 represents the reverse side thereof.

The design upon the obverse side of the medal consists in medallions appearing to overlap, one of the medallions bearing a representation of the bust of Christopher Columbus and the other a representation of the bust of George Washington. An eagle apparently rises from the rear of the medallions, holding in its beak a scroll, the eagle being seemingly in the act of flying; and beneath the medallions an olive branch is depicted. The branch,

the medallions, the figures upon the medallions and the eagle appear as in relief upon the body of the medal.

With reference to the reverse side of the medal, the design thereon set forth consists of a heroic figure representing Liberty gazing at a cross apparently displayed in the sky, and rays from the cross are apparently directed upon the figure of Liberty and upon the representation of the grounds and buildings of the Columbian Exposition, the latter appearing at the back of the figure.

I claim—

A design for a medal, substantially as herein set forth.

CESAR ORSINI.
